UNITED STATES PATENT OFFICE.

GAIL G. CURRIE, OF LOS ANGELES, CALIFORNIA.

FAN WHEEL.

Application filed March 7, 1921. Serial No. 450,289.

This invention relates to exhaust fan wheels for moving large volumes of non-liquid fluids.

An object of the invention is to increase the efficiency of fans of that character.

Fans of this character are driven by belt drive or direct connected motors and for the purpose of this description, it will be shown as constructed to be direct driven by an electric motor. The fan may be positioned in any manner desired and which is best adapted for the service required; and its axis of revolution may extend in any direction.

15 Certain terminology relating to the fan is therefore somewhat arbitrary in the present specification and claims, and to avoid confusion, certain directions relative to the fan and the translation of motion are termed as follows:

Onward signifies the direction in which the current of air is driven by the fan; front signifies the surface the air leaves in its onward course; back and backward indicate the opposite of front and onward; forward refers to the direction the blades of the fan move relative to the edges, surfaces or parts of the blades that cut the air; rearward and rearwardly signify the opposite direction of forward; center and inner refers to the portion of the fan adjacent the hub; and outer, the direction and locus away from the hub.

This invention is broadly new, basic and pioneer in that the fan wheel comprises fan blades having dentated forward edges and having front faces formed with loops or cavities, the front floors of which slope from the dentations onwardly, forming between said dentations a channel at the back of the blade so that air pressure on the back of the blade will be supplied to the back of both of the loops from the adjacent edges of the loops; and I have found by experiment that the most effective place at which to locate said channel, is about a half to two-thirds of the way from the rim to the hub of the wheel. By this construction, the tendency to vacuum produced by each revolving blade will be supplied more readily and directly, and the resistance to revolution of the wheel is thereby decreased.

By this construction, the wheel is provided with an inner and an outer circle or

set of outwardly and onwardly diminishing 55 loops having floors that slope onward from the air cutting edge, and onward in the direction of air propulsion, the floors of the innermost cavities being at a greater angle with the plane of rotation than the floors of 60 the outermost set of said cavities, and being adapted to pick up the air and act upon it at a greater angle than any other part of the blade, and to drive it forward at a greater initial velocity than would be given 65 if the floor was at a less angle than the floors of the outer set of cavities.

By this novel construction and arrangement, the volume of air driven onward at the central part of the wheel is increased, 70 and, a greater volume of air will be driven onward by a predetermined amount of power than with former fan wheels.

The inner loops of greater pitch serve to offset the decrease in peripheral velocity at 75 the shorter radius, thus moving onward a greater amount of air with a minimum expenditure of horsepower.

In common practice the blades may or may not extend to the hub of the wheel. 80

An object of this invention is to make provision whereby the tendency of the fan blades to create a vacuum behind the blades will be offset by a full supply of air under atmospheric pressure to the back of the 85 blades in the most efficient manner; and this I accomplish by providing an abrupt rearward offset or detent in the front edge of the blade near the inner end thereof and producing a loop extending from said offset to the rear edge of the blade so that the bottom of the loop operates as an air propelling element arranged at a more abrupt angle than the outer portions of the blades thus to increase the volume and velocity of 90 the air moved onward by the blades near the center of the wheel.

The angle of the rear face of the blade at the junction of the offset with the main body of the blade forms a back channel to 100 receive atmospheric air and to distribute it over the back of the blade on both sides of said channel extending from the forward to the rear edge of the blade; thus practically eliminating any retardation of the motor by 105 reasons of vacuum at the back of the blades.

The invention includes the combination with the outer curved pockets of the fan

blades, of off-sets at a different plane to pick up air at a peripheral speed lower than that of the rim of the wheel.

Other objects, advantages and features of 5 invention may appear from the accompanying drawing, the subjoined detail description and the appended claims.

The accompanying drawing illustrates the invention.

10 Figure 1 is a fragmental section on line indicated at x^1 , Figs. 2 and 3, showing the fan attached to a motor.

Fig. 2 is a reduced rear view of the fan detached from the motor and support.

15 Fig. 3 is a front view of the fan shown in Fig. 2.

Figs. 4, 5 and 6 are sections on the respective lines x^4 , x^5 , and x^6 , Fig. 3, looking in the direction of the arrows, respectively.

20 Fig. 7 is a view of a blank from which one of the direct blades may be bent up.

Fig. 8 is a detached view of a blade formed by bending up the blank shown in Fig. 7.

The fan A is mounted in a suitable frame 25 B and is connected to a motor 1 housed in a suitable casing 2 which may or may not have ventilating apertures 3 in the front face thereof. Extending from the motor and rotatably mounted in the bearing 4 is

30 the shaft 5 on which is fixed the hub 6 with spokes 7 preferably connected together at their outer ends by means of a circular rim 8 which is attached to the direct blades 9 by suitable means as by rivets 10. Said

35 blades 9 are straight at the inner portions near the hub and form an outer detent a and an air impelling surface b sloping to the plane of the rim 8, and the contour of the back c and also the forward cutting edge d

40 of each blade is broken by the loop e ; the cutting edge f of which is located so far from the rear edge that the pitch of the loop e from its cutting edge f to the rear edge g is at a greater angle to the plane of

45 rotation than is the floor of the outer loop and there is a channel 11 at the back of the blade between the loops. The bottom 13 of the loop e extends or slopes backward and onward so as to produce a current of air in

50 the onward direction; that is, away from the motor in parallelism with the axis of rotation, and increases the volume of the onwardly propelled current of air. I have provided the direct blades of my fan with

55 looped dentate forward edges, the loops constituting depressed portions a , d , e and f , the loops e , f having side walls 11 and 12 and bottoms 13 sloping from their front retracted edges d , and f rearwardly with relation to the direction in which the wheel rotates and onward in the direction of the current of air, the loops or dentations f , thus forming supplementary air impelling faces at a greater angle to the plane of rotation,

60 than the main bodies 9 of the blades.

By this construction the fan blades are adapted to cause a considerable increase in the volume and velocity of the current of free air amounting to about 25%, more or less.

70 The parts 14 act as braces to the blades 9, and increase the rigidity of their attachment to the spokes. By this construction and arrangement, a channel 15 is provided on the back of the blades at the meeting edges of the loops; and as the fan wheel rotates, the forward points of the dentated edges of the blades cut the air before the edge of the back channel 15 so that air is allowed to flow to the inner portion of the 75 back face of the outer loop and on the outer portion of the back face of the inner loop, thus allowing air pressure to be applied over the back of the blades from an intermediate point, thus relieving the vacuum 80 more completely than has heretofore been the case in fan wheels.

85 In practical operation the fan wheel is rotated in the direction indicated by the large curved arrows in Figs. 2 and 3. The direct blades with their outer and inner loops a and f drive the air onward with marked increase over blades not having the inner pockets.

90 In the drawings the outer loops are shown as extending about two-thirds of the way from the rim toward the hub and the channels 15 between the loops a and f extends from the forward edges of the blades to rearward edges respectively. It is thus seen 95 that I have not only succeeded in increasing the volume of air impelled by the wheel, but have also delivered the vacuum at the back of the wheel, thus taking a measure of strain off of the shaft.

100 I claim:

110 1. A fan wheel comprising fan blades the rear edges of which are in a common plane and the forward edges and front fans of which blades are formed with dentations; the forward faces of said blades being respectively formed with outer and inner loops and there being channels at the backs of the blades between the dentations and loops.

115 2. A fan wheel comprising a rim, a hub, and radial spokes between the hub and rim; and also comprising fan blades, the rear edges of which are fixed to the spokes respectively, and the forward edges of which blades are formed with dentations; the forward faces of said blades being respectively formed in loops sloping onward respectively from the dentations to the plane of the spokes and rim.

120 3. A fan wheel comprising a rim, a hub, and radial spokes between the hub and rim; and also comprising fan blades, the rear edges of which are fixed to the spokes respectively, and the forward edges of which 130

blades are formed with major and minor dentations; the forward faces of said blades being respectively formed in major and minor loops sloping onward respectively from the major and minor dentations to the plane of the spokes and rim.

4. A fan wheel comprising a rim, a hub, and radial spokes between the hub and rim; and also comprising fan blades, the rear edges of which are fixed to the spokes respectively, and the forward edges of which blades are formed with dentations; the forward faces of said blades being respectively formed in loops sloping onward respectively from the dentated edges to the spokes and to the plane of the rim; said major dentations and loops occupying approximately two-thirds of the space between the rim and hub of the wheel.

5. A fan wheel comprising a rim, a hub, and radial spokes between the hub and rim; and also comprising fan blades, the rear edges of which are fixed to the spokes respectively, and the forward edges of which blades are formed with dentations; the forward faces of said blades being respectively formed in loops sloping onward respectively from the dentated edges to the spokes and to the plane of the rim, said major dentations and loops occupying approximately two-thirds of the space between the rim and hub of the wheel; and the pitch of the floors of the loops being greater than that of the floors of the major loops.

6. A fan wheel provided with sheet metal blades, the front edges of which are bowed rearwardly for a distance from the rim

and then returned approximately to the plane produced from the rim and there provided with a rearward offset to pick up the air near the hub of the wheel; the rear edge of the blade being practically straight and in the said plane of the rim of the blade.

7. A fan wheel comprising a rim, a hub, and radial spokes between the hub and rim; and also comprising fan blades, the rear edges of which are fixed to the spokes respectively, and the forward edges of which blades are formed with major and minor rearward dentations; the forward faces of said blades being respectively formed with major and minor cavities extending respectively from the major and minor dentations to the plane of the spokes and rim, said major dentations and concavities extending approximately two-thirds of the distance from rim to hub of the wheel.

8. A revolving fan wheel in which the front edges of the blades are offset near the axis of revolution.

9. A fan wheel comprising fan blades having dentated forward edges and having front faces formed with loops or cavities having front floors sloping from the dentations onwardly, said front floors forming a channel at the back of the blade so that air pressure on the back of the blade will be supplied to the back of both of the loops from the adjacent edges of the loops.

In testimony whereof, I have hereunto set my hand at Los Angeles, California, this 24th day of February, 1921.

GAIL G. CURRIE.
